UNITED STATES PATENT OFFICE.

CHARLES HOWARD FOWLER AND EDWARD ARNOLD MEDLEY, OF GREAT CROSBY, LIVERPOOL, ENGLAND.

APPARATUS FOR SUBJECTING GAS OR VAPORS TO THE ACTION OF LIQUIDS.

No. 928,118.

Specification of Letters Patent. Patented July 13, 1909.

Application filed December 10, 1908. Serial No. 466,879.

To all whom it may concern:

Be it known that we, CHARLES HOWARD FOWLER and EDWARD ARNOLD MEDLEY, subjects of the King of Great Britain, both residing at Great Crosby, Liverpool, in the county of Lancaster, in the Kingdom of England, have invented certain new and useful Improvements in Apparatus for Subjecting Gas or Vapors to the Action of Liquids, of which the following is a specification.

In our British patent specification No. 22282 of 1902, we described an apparatus for subjecting gas to the action of a spray of water. This apparatus consisted essentially of a vertical cylindrical case, closed at the ends, within which revolved a vertical shaft to which were fixed two or more horizontal circular disks, of a diameter smaller than the internal diameter of the case, so that there was an annular space around each revolving disk. Between each pair of revolving disks was a stationary tray or dish, preferably conical in shape, the apex of the cone pointing downward, the outer diameter fitting closely to the case and the revolving shaft passing through a hole in the center of the tray with ample clearance for gas and water to flow as hereinafter described. Water was fed from a supply pipe on to the uppermost revolving disk near to its center, and revolving with it was whirled off from its circumference in a finely divided spray. This spray after dashing against the wall of the case fell on to the tray below and ran down it toward the shaft, until reaching the hole in the center of the tray it fell through on to the disk revolving beneath, which again threw it off as a spray at its circumference. And this process was repeated for as many disks and trays as the apparatus contained, the water descending from disk to tray and from tray to disk until it reached the bottom and left the apparatus through a suitable trap. The gas followed the same path as the water but preferably in the opposite direction. Entering the apparatus at the bottom it passed through the annular space between the case and the lowest revolving disk, meeting there the spray thrown off by the disk, thence guided by the tray above the disk the gas traveled toward the shaft, passed through the hole in the middle of the tray and thence flowed to the annular space around the next revolving

disks, where it was again subjected to the water spray. And this process was repeated until the gas having passed all the disks left the apparatus by a suitable discharge pipe.

It is clear that this apparatus can be used with other liquids as well as with water and the present invention is for an improved form of this apparatus by means of which the amount of spraying by water or other liquids to which the gas or vapor is to be subjected is greatly increased without much increasing the size of the apparatus. We effect this by substituting for each single revolving disk a number of such disks, fixed one above the other and separated from each other by a short space. And thus instead of a single spray from the periphery of a single disk we obtain a layer of sprays from the peripheries of a group of disks. Means must be employed for bringing to each of the several disks forming a group its proper supply of liquid. The drawings set forth our latest designs for this purpose.

Figure 1 shows a vertical section of our apparatus; Fig. 2, a plan view of the trays for general purposes, while Fig. 3 is a section, and Fig. 4 a plan of a modified form of tray.

Referring first to Figs. 1 and 2, the bottom disk A of a group of disks A, B, C, D, is fixed to the vertical shaft S and the upper disks of the group B, C, D, are attached to the disk A. The upper disks B, C, D, have each one a central hole larger than that in the disk immediately beneath it, that is, the hole through the center of disk D, is larger than the hole through the center of the disk C, and the hole through the center of the disk C is larger than the hole through the center of the disk B. Above each group of disks is fitted a conical tray T, the hole in the middle of which is so shaped that some of the liquid running down the tray is delivered on to each of the disks revolving below. Thus, referring to Fig. 2, which shows a plan of a tray and group of disks, the liquid running over the edge a, b, of the hole a, b, c, d, h, g, f, e, in the middle of the tray falls through the holes in the centers of the disks B, C, D, on the bottom disk A. The liquid running over the edge, c d, falls on the disk B. The liquid running over the edge, e f, falls on the disk C, and the liquid running over the edge, g h, falls on the disk D. Thus each disk

of the group of disks receives its proper proportion of the liquid running down the tray above the group, and it is clear that this method can be adopted for groups of disks 5 consisting of a greater or less number than four.

The liquid can be delivered in a convenient manner over the upper surface of the top tray T, by allowing it to fall from the supply pipe P on to a single revolving disk E. After the liquid has been sprayed from the peripheries of the uppermost group of disks A, B, C, D, it falls on to the tray below, which delivers it to the next group, and so 15 on for as many groups of disks as the apparatus contains in exactly the same manner as we described in our specification No. 22282 of 1902. The liquid leaves the apparatus by the pipe Q, which can be suitably 20 trapped, and if desirable the liquid can be raised by means of a pump to the supply pipe P, and again circulated through the apparatus. The gas or vapor to be treated enters the apparatus by the pipe R, and 25 leaves it by the pipe U.

Referring now to Figs. 3 and 4:—These show a form of fixed tray having an opening for the gas to pass through not merely at the center, but at the circumference also 30 so as to allow of a shorter and freer passage for the gas through the machine. Also to insure even distribution of the liquid it is desirable to divide from each other by means of radial ribs the several sections of the tray 35 which feed the corresponding disks revolving below. These ribs or arms M alone connect the tray with the circumferential ring N which latter is firmly fixed to the cylindrical casing, so that there is a circular conduit 40 for the passage of the gas around the edge L, while the sprayed liquid runs off the upper surface of the ring N and falls on to the tray and thence is delivered on to the revolving disks. It is also desirable to 45 so shape the perforation in the center of the tray that each revolving disk is fed with liquid in two or more places diametrically opposite to each other. Thus in Fig. 4 the segments H H feed one disk, the segments 50 I I a second, the segments J J a third and the segments K K a fourth. The object of this double feed is to distribute the liquid more evenly over the disks than is the case when each disk is fed from a single segment.

55 We declare that what we claim is:—

1. In apparatus for subjecting gas or vapor to the action of liquids, the combination of a closed chamber, a vertical shaft, a set of horizontal disks rigidly carried by said 60 shaft, and fixed only a short distance from each other, and means for supplying each of the disks near the center with a substantially equal part of the liquid supplied and means for passing the gas to be treated through the

apparatus and past the peripheries of these 65 disks.

2. In apparatus for subjecting gas or vapor to the action of liquids, the combination of a closed chamber, a vertical shaft, a disk fixed to said shaft, a feed pipe delivering on 70 to said disk, whereby the feed is evenly distributed all around, a funnel for collecting the distributed feed, having a plurality of exit edges substantially evenly spaced rigidly around the center, and a plurality of 75 disks below, carried by said shaft, each receiving the liquid from one of these exit edges and means for passing gas up past the edges of these disks.

3. The combination of a closed chamber, 80 a vertical shaft, a disk fixed to said shaft, a feed pipe delivering on to said disk, whereby the feed is evenly distributed all around, a funnel for collecting the distributed feed, having a plurality of exit edges substantially evenly spaced rigidly around the center, and a plurality of disks below, carried by said shaft, each receiving the liquid from 85 one of these exit edges and means for passing gas up past the edges of these disks, 90 similar funnels and pluralities of disks below the above on the same shaft, substantially as described.

4. In a funnel for the purposes described, 95 the combination of a series of division plates M dividing the funnel circumferentially into equal divisions, and a funnel plate having delivering orifices between each pair of divisions arranged at two or more distances from the center substantially as described. 100

5. In a funnel for the purposes described the combination of a series of division plates M, dividing the funnel circumferentially into equal divisions, and a funnel plate having delivering orifices between each pair of 105 divisions arranged in sets, the exits of each given distance from the center alternating with those of other given distances from the center substantially as described.

6. In an apparatus for treating gases with 110 liquids the combination of a cylindrical closed chamber, a shaft traversing this chamber centrally, a plurality of sets of disks, each set fixed to the said shaft, and a funnel above the said disks, and between 115 each set of disks delivering the liquid to be treated evenly to each of the superimposed disks of the set substantially as described.

In witness whereof, we have hereunto signed our names this 1st day of December 1908, in the presence of two subscribing witnesses.

CHARLES HOWARD FOWLER.
EDWARD ARNOLD MEDLEY.
